Primary Examiner — Brian N Vinson(74) *Attorney, Agent, or Firm* — Young & Thompson(57) **CLAIM**

The ornamental design for a support for stemmed glasses, as shown and described.

DESCRIPTION

FIG. 1 is a perspective view of a support for stemmed glasses showing my new design;

FIG. 2 is a perspective view thereof from the side opposite that shown in FIG. 1;

FIG. 3 is a top plan view thereof;

FIG. 4 is a bottom plan view thereof;

FIG. 5 is a side elevational view thereof;

FIG. 6 is a side elevational view thereof from the side opposite that shown in FIG. 5;

FIG. 7 is an end view thereof; and,

FIG. 8 is an end view thereof from the end opposite that shown in FIG. 7.

The material shown in broken lines forms no part of the claimed design.
